UNITED STATES PATENT OFFICE.

JAMES J. FLANNERY, JR., OF PITTSBURGH, PENNSYLVANIA.

TRAFFIC SIGNAL.

Application filed May 11, 1923. Serial No. 638,202.

To all whom it may concern:

Be it known that I, JAMES J. FLANNERY, Jr., a citizen of the United States, and a resident of Pittsburgh, in the county of Allegheny and State of Pennsylvania, have invented a new and useful Improvement in Traffic Signals, of which the following is a specification.

This invention relates to signaling devices, and particularly to a traffic signaling device of the type employed for directing and regulating traffic at the intersection of streets or under other similar conditions.

It is an object of the invention to provide a traffic signaling device which is of sturdy construction, neat in appearance, easy to manipulate, and highly efficient in operation.

It is a special object to provide a device of the character referred to which will afford protection to the operative against exposure to the elements, if desired, while at the same time permitting him to readily observe and conduct the traffic, the protecting means employed being of a removable nature enabling the same to be detached and stored away when not required.

It is also a special object to provide a device equipped with a supporting base in the form of a storage compartment, the top of which will also serve as an elevated platform on which the operative may stand.

It is a further special object to provide a device in which the signaling element proper also functions as a canopy or top, and in which the actuating means therefor is of such character that upon the release thereof by the operative, as is frequently necessary in case of accidents at which time the operative must leave his station at the signaling device, the indicating element of the signal will be automatically locked in a fixed position indicating the right of passage for traffic in but a single direction.

It is still a further special object to provide a device which is self-contained, and equipped with suitable lighting means so arranged as to render the device effective for night signaling as well as for use during the day.

These and other objects of the invention will more fully appear when taken in conjunction with the following description and the appended claims.

In the accompanying drawings, Fig. 1 is an elevational view, with parts broken away,

illustrating the preferred embodiment of the invention; Fig. 2 a fragmentary view illustrating one of the indicating signals forming a part of the combined canopy and signaling element; Fig. 3 a transverse sectional view taken through the upper portion of the device illustrated in Fig. 1, showing the method of rotatably mounting and supporting the canopy signal; Fig. 4 a transverse sectional view taken on the line IV—IV of Fig. 1; and Fig. 5 an elevational view illustrating a modified form of the invention.

Referring to the embodiment illustrated in Figs. 1 to 4, the supporting base which is in the form of a storage compartment is indicated generally by the reference numeral 1, consisting of the bottom or floor portion 2, the top 3, and the side wall 4, all of which cooperate to form a hollow storage compartment such as clearly indicated in the drawings. Although the base 1 may be made in various forms, it is preferably cylindrical in shape whereby it can be more easily moved from place to place by rolling along the lower peripheral edge of the compartment in a well known fashion. One side of the compartment is provided with an opening of considerable size which is equipped with the door 5, hinged at 6, 6', and adapted to be maintained in closed condition by means of the lock device 7. The top 3 besides forming a closure for the upper end of the storage compartment, also serves as an elevated platform on which the officer or operative in charge of the signaling device may stand.

Fixed centrally of the platform 3 in any suitable manner as by the cylindrical socket 8, is an upright hollow main standard 9 equipped at a point adjacent its upper end with a bearing boss 10 which is adapted to cooperate with a bearing boss 11 surrounding the upper extremity of the standard and superposed upon boss 10. The two bearing bosses are provided with raceways formed in their adjacent faces for the reception of the anti-friction balls 12. At the extreme upper end of the standard 9 is mounted a lighting device of any suitable nature, that illustrated in the preferred embodiment being an electric lamp indicated at 13, the source of supply for the electric lamp being obtained from a storage battery 14 located within the compartment of the base. The storage battery 14 and the lamp 13 are operatively connected with each other by

means of suitable wiring indicated at 14' which passes upwardly through the bore of the standard 9.

Attached to the bearing boss 11 are a plurality of radial arms 15, 15', 15" and 15'', the boss 11 and the radial arms together forming a supporting spider on which to mount the combined canopy and indicating signal 16. The canopy-signal 16 is dome-shaped and is preferably made as a stamping from sheet metal having desirable properties for this purpose. The lower edge of the canopy is adapted to rest upon the radial arms whose outer ends are bent upwardly for a short distance in the manner indicated at 17, 17', for embracing the lower edge of the canopy, and the bent ends of the arms are preferably rigidly connected with the canopy by means of set screws or other similar devices 18. A portion of the material of the canopy 16 is removed or stencilled out at appropriate points about midway of its height so as to form the desired designating signals. One of these signals is clearly shown in Fig. 1 forming the word "Stop." Two such designations are formed at diametrically opposite points, and likewise located at diametrically opposite points spaced at 90° from the words "Stop" are similar designations forming the words "Go." These stencilled out words are backed by the transparent plates 20, 21, 20' and 21', the plates 20 and 20' being disposed behind the words "Stop," while the plates 21, 21' are disposed behind the words "Go." All of these plates are colored in a distinctive manner corresponding to the traffic regulations at the point at which the signaling device is to be used, it being customary in many localities to use red in conjunction with the "Stop" designations and green in conjunction with the designations "Go." In addition to the stencilled out designations just described, other portions of the canopy 16 may be stencilled out for the purpose of conveying information to the traffic to be regulated. An example of one such additional designation is clearly indicated in Fig. 1, in which the lower portion of the canopy is stencilled out to form the following designation "Pedestrians, please cross with traffic." The last named designation is preferably formed of openings of reduced size, and may be backed by a suitable backing plate, either plain or colored, similar to the plates 20, 20', 21 and 21', or the backing plate may be dispensed with, if desired.

The actuating means for rotating the canopy-signal, consists of a shaft 22 to which a pair of yokes or bands 23, 23' encircling the standard 9 are attached, the lower band 23' resting upon a collar 24 fixed to the standard. The upper portion of the shaft 22 immediately below the bearing boss 10 is bent laterally as at 25 and is again turned

upwardly to form end 26 which is adapted to engage and fit within a socket 27 formed upon the lower face of the arm 15''. Pivotally attached as at 28 to the lower extremity of shaft 22 is a handle 29, the pivotal connection 28 being of such nature that the handle 29 is constantly urged to assume the position shown in dotted lines 29', Fig. 1, under the influence of gravity.

Formed integrally with and at one side of the collar 24 is a segmental flange 30 which extends outwardly and lies immediately below the pivotal point 28. This flange is notched at the points 31 and 32, spaced 90° from each other, and are designated "Go" and "Stop," respectively, as clearly shown in Fig. 4. When the handle 29 is either forced downwardly by the operative or falls downwardly under the influence of gravity, the same will be projected within one of the slots when the canopy-signal and its actuating mechanism is moved angularly to either one of the positions which it is intended to occupy for properly displaying the "Go" or "Stop" designations formed in the canopy.

The top 3 is provided adjacent its periphery with a series of spaced apertures or openings 33, and immediately below and in vertical alignment with these openings are straps or retaining clips 34 suitably attached to the vertical side wall 4 of the compartment-base. These openings 33 and the clips 34 serve as guiding and retaining means for a plurality of auxiliary upright standards 35 which are adapted to project through the openings 33 and the retaining clips with their lower extremities resting within an annular depression 35 formed at the periphery of the bottom or floor 2. Any number of these auxiliary standards may be employed, the number depending entirely upon the size of the signaling device and the character of the materials employed, eight being illustrated in the embodiment shown. The auxiliary standards are intended to serve as supports for a screen or curtain 36 which is attached and supported from the standards in any suitable manner as by means of the fastening devices illustrated at 37, 37', these fastening devices being of a conventional type commonly employed in connection with curtains of automobiles or other similar vehicles, and comprises an attaching lug or button which is adapted to pass through and cooperate with properly formed eyelets in the body of the curtain. The screen or curtain 36 may extend completely around the entire signaling device or only partially therearound as is found convenient. The outer ends of the auxiliary standards terminate at a convenient height such as indicated at 38, whereby to leave the upper portion of the operative disposed thereabove. Customarily the upper ends of

the auxiliary standard 35 will terminate slightly above the waist of the operative so as to leave his vision entirely unobstructed while at the same time affording protection for the lower portion of his body. In order to afford more adequate and complete protection in case of storms, an additional set of auxiliary standards such as shown at 39 is provided, these additional auxiliary standards being adapted to be connected to the upper ends of the standards 35 by means of attaching sleeves 40, the sleeves 40 being slipped onto the upper extremity of the standards 35 and the lower ends of the standards 39 then engaged telescopically with the sleeve whereby when the two standards are thus connected, one forms in effect a continuation of the other. A screen or curtain 41, similar to the curtain 36, is employed in connection with the upper standards, being attached in an analogous manner by means of attaching devices 42, 42'. The upper curtain 41 is provided at a suitable point intermediate its ends with a series of flexible transparent windows 43 which permit the operative to at all times observe the traffic to be regulated. The curtains are preferably made of canvas or other suitable waterproof flexible fabric.

30 In the modified form of the invention illustrated in Fig. 5, the supporting base consists of a compartment 50 which is in the form of an elongated cylinder with a dome-shaped upper portion 51, the cross sectional dimension of the casing being comparatively small relative to that illustrated in connection with the preferred embodiment. The base-compartment 50 in the modified form is likewise provided with a closure door 52 hinged as at 53, 53' and 53'', and adapted to be held in closed condition by the lock 54, similar to the method employed in connection with the previously described form.

45 The central portion of the top or dome 51 is in the form of a cylindrical socket 55 which is adapted to receive the upstanding hollow standard 56 which is supported in operative position on the base, the extreme upper end of the standard being equipped 50 with a lighting fixture 57, which in this instance is illustrated as an acetylene burner, the supply of gas therefor being secured from a tank 58 located within the compartment of the base. The gas is conveyed from 55 the tank 58 to the burner through a suitable pipe 59 which may be connected with the upper end of the tank in any well known or desirable manner at the point 60 as will be obvious from an inspection of the drawings.

60 In the modified form, the method of mounting the canopy, and the means for actuating and locking the same correspond to those in the preferred form, and are mere counter-parts in details of construction with 65 those previously described. For this reason,

these parts will not be described in greater detail, but have been designated in Fig. 5 of the drawings by means of the same reference numerals with the addition of an exponent "a" thereby clearly identifying the 70 various elements.

The operation of the preferred form illustrated in Figs. 1 to 4 is obvious from the above description. The signaling device is located at any desirable point with the designating signal characters positioned so as to be easily observed by the traffic to be regulated, in other words, the signaling device is disposed so that either the designating signal character "Stop" or "Go" will be positioned 75 so as to be observed by the traffic when the actuating handle is moved into engagement with the corresponding notch 30 or 32, as the case may be. With the device so positioned, movement of the handle throughout an arc of 90° so as to change the same from the one notch to the other, results in rotating the canopy-signal 16 so as to present the proper designating character to the traffic, thus indicating thereto the intention of the operative 80 in an obvious manner, and corresponding generally to the scheme now commonly employed for directing traffic.

During the operation, the operative stands upon the top or platform 3 in an elevated position which is not only helpful in aiding him to observe the traffic, but obviates the necessity of standing directly upon the ground or street during wet or cold weather, thus adding to his comfort.

95 If the protecting screens or curtains are not desired, the same may be readily removed by detaching the curtains after releasing the fastening devices 37, 37', 42, 42' and withdrawing and disconnecting the auxiliary standards 35 and 39 from each other and from the supporting base. With the parts thus removed and separated, the same may be packed into a small space and stored away for future use. Preferably the compartment provided in the supporting base is of sufficient size for this purpose.

100 With the exception of the method of utilizing the protective curtains or screens, as well as the supporting platform, the operation of the modified form of the device shown in Fig. 5 corresponds to that of the preferred form. With the modified form the operative merely stands adjacent the base-compartment 50 and actuates the handle 29^a for the purposes of displaying the proper designating signal, the canopy-signal 16^a serving as a protecting top or umbrella in an obvious manner. Although the 105 gas supply tank shown in connection with this form occupies substantially the entire space within the compartment, it is noted that smaller tanks may be employed, if desired, in which case several may be stored 110 in the compartment at one time, and sev-

erally connected to the supply pipe 59 as occasion may arise.

In both embodiments illustrated, the canopy not only functions as a protective top and indicating signal, but the interior surface thereof functions as a deflector to throw the light from the lighting fixtures downwardly upon the operative, and to enhance its action in this respect the interior surface of the canopy may be polished to a greater or less extent as will prove most satisfactory for the conditions under which it is employed.

It is thus seen that the invention provides a sturdy and compact structure which is neat in appearance, easy to manipulate and will function in an efficient manner for the purpose of directing traffic in the desired direction, and at the same time provides a device which affords ample protection to the operative against undue exposure, and a self-contained structure which is capable of being used effectively for night signaling as well as for use during the day.

25 I claim:

1. A self-contained traffic signaling device comprising a portable base, a stationary supporting standard fixed thereto, a combined protective canopy and indicating signal rotatably mounted on said standard, and means for rotating the same.

2. A self-contained portable traffic signaling device comprising a hollow base serving as a storage compartment, an upright standard fixed to the top of said compartment, whereby not to obstruct the interior thereof, a combined protective canopy and indicating signal rotatably mounted on the standard, means for actuating the canopy signal, and means for locking the said actuating means.

3. A traffic signaling device comprising a base, an upright supporting standard fixed

to said base, a combined canopy and indicating signal rotatably mounted at the upper end of the standard, means for rotating the said canopy signal, a handle pivotally attached to the said means and normally urged to assume substantially vertical position under the influence of gravity, and a notched retaining element disposed below the handle and in the path of movement thereof, whereby upon release of the handle by the operative, the same will swing downwardly and engage one of the said notches to prevent movement of the said signal.

4. A traffic signaling device comprising a base the upper surface of which is in the form of an elevated platform, a main supporting standard fixed centrally of the platform, a combined canopy and indicating signal rotatably mounted at the upper end of the standard, means for actuating the canopy signal, and a protective screen or curtain interposed between the platform and signal but discontinued from the signal and spaced from the main standard.

5. A traffic signaling device comprising a base the upper surface of which is in the form of an elevated platform, a main supporting standard fixed centrally of the platform, an indicating signal rotatably mounted at the upper end of the standard, means for actuating the signal, the upper surface of the platform being provided adjacent its periphery with a plurality of guide openings, upright auxiliary standards removably engaging said openings, and a protective screen or curtain attached to the said auxiliary standards.

In testimony whereof, I sign my name.

JAMES J. FLANNERY, JR.
